(57) **CLAIM**

The ornamental design for a lamp with hanger assembly, as shown and described.

DESCRIPTION

FIG. 1 is a perspective view of a lamp with hanger assembly showing my design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof; and,

FIG. 8 is a perspective view showing a lamp with hanger assembly in an alternate configuration.

The broken lines in the drawings are for the purpose of illustrating portions of the lamp with hanger assembly that form no part of the claimed design.

1 Claim, 5 Drawing Sheets
